Primary Examiner — Keith J Wilson

(57) **CLAIM**

The ornamental design for shower head, as shown and described.

DESCRIPTION

FIG. 1 is a top front perspective view of a shower head showing the claimed design;

FIG. 2 is a bottom front perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged partial view A of FIG. 1; and,

FIG. 10 is an enlarged partial view B of FIG. 8.

The broken line representations of spray nozzle holes in FIGS. 1-6, 8 and 10 in the figures are for the purpose of illustration only, and form no part of the claimed design. The broken lines in the figures illustrate portions of the shower head that form no part of the claimed design. The dash lines in FIGS. 1 and 8-10 are for the purpose of depicting the enlarged view and form no part of the claim.

1 Claim, 10 Drawing Sheets
